UNITED STATES PATENT OFFICE

JUNIUS D. EDWARDS, OF OAKMONT, PENNSYLVANIA

METHOD OF PRODUCING PRINTING PLATES

Application filed July 31, 1929. Serial No. 382,596.

My invention pertains to a method of producing printing plates. The invention is particularly applicable to the production of printing plates such as have heretofore been produced by applying cut-out portions of 5 rubber, linoleum, or like material to a suitable base, or by removing such materials from a base covered therewith, so as to leave the design to be impressed standing in relief.

10 Printing plates having the impression parts thereof formed of rubber, linoleum and kindred substances are in common use. They are considered advantageous, for instance, where relatively large tint areas are to be 15 printed, one reason being that the resilience of these materials reduces the amount of "make ready" which is necessary and enables an even tint readily to be printed. Another, and a growingly important, use of such printing 20 plates is in connection with the process of printing by means of the so-called "water-color" inks, which process is ordinarily carried on along the lines of Patent No. 1,595,756 granted to Jeane Berté Inc., and is 25 generally known as the Jean Berté process. Printing plates having metallic surfaces are found not to accept these "water-color" inks with readiness, and plates having the impression portions formed of rubber, linoleum, or 30 the like, are commonly employed.

In producing such a plate for the Jean Berté process, for instance, the operator is supplied with a key proof from which he takes an impression upon the rubber surface 35 of a composite plate formed by cementing a rubber sheet upon a metallic base. With the impression as a guide, he then cuts away, with a knife or other suitable tool, all of the face of the rubber except those portions from which 40 the impression is to be taken. He often has to cut up the composite plate, since different parts thereof will frequently be used for different colors. The result, for any one color of a color printing job, is usually a plurality of 45 metallic plates each carrying, in relief rubber, a portion of the design to be printed. These plates are generally assembled on "patent bases" and are adjusted in position on the latter until they occupy precisely the correct 50 location for the design, to register, for in-

stance, with another color. Evidently, the time, labor and skill necessary to produce such plates and set them up correctly in the form is very great, and adds considerably to the cost of carrying on work of this character.

It is the prime object of my invention to provide a mode of producing printing plates, which obtains the desired results in connection with resilience and receptiveness to the 60 so-called "water-color" inks, and avoids the long and tedious steps heretofore necessary in producing and setting up plates employed for kindred uses.

According to my invention I coat a base 65 with rubber, or a rubber compound or derivative, or other organic substance, ordinarily of a colloidal nature, capable of being applied by electro-deposition; and I apply this coating in such a manner that the design to 70 be impressed stands in relief. One method by which this may be effected is as follows: An ordinary zinc etching is made, having, of course, in relief, the design which is to be impressed. The low parts of such etching 75 are then coated with insulating material such as an insulating varnish. This may conveniently be done by coating the whole plate with varnish and thereafter polishing the varnish away from the relief portions of the 80 plate. Such relief portions being duly cleaned, the plate is introduced, in contact, in this instance, with the anode, or constituting such anode, into a rubber emulsion in an electro-depositing bath of the general character disclosed in United States Patent No. 1,476,374 dealing with the electro-deposition 85 of rubber coatings. Such bath may, if desired, be made to contain the requisite elements for subsequent vulcanization of the 90 rubber by the mere application of heat. The coating of rubber will be deposited only upon those parts of the zinc etching which are unprotected by the insulating varnish,—that is to say, the relief parts corresponding 95 to the design which is to be impressed, with the result that a plate is produced in which rubber portions corresponding to the design to be impressed stand in relief.

After the plate has been thus produced it 100

is removed from the depositing bath and washed, whereafter it may be toughened by vulcanization. If the emulsion in the depositing bath has contained a vulcanizing agent, such vulcanization can be effected by the application of heat. Otherwise, suitable gaseous vulcanizing agents are employed in a well known manner. If found necessary, a suitable preliminary coating may be applied, 10 in accordance with well understood principles in the art of rubber deposition, to insure a firm adherence of the subsequently deposited rubber to the metallic base.

15 A printing plate according to my invention can thus be produced with relative ease, and, moreover, containing the whole of any desired design, can be set up in the form, to register, for instance, with other colors of the job, quite easily.

20 I contemplate that it will not be necessary, in many instances, to apply the insulating coating to the zinc or other etched plate, though the employment of such coating tends towards good definition, and such coating 25 can be removed, after deposition has taken place, if desired. The relief of the rubber coating will follow the relief of the original etched plate to a sufficient extent to fulfill the printing requirements in many cases. I 30 further contemplate that it may not be necessary to employ an etched plate as a base, since a flat base may be given (for instance, through a photographic process) an insulating coating over those parts thereof from 35 which an impression is not to be taken,—i. e. those parts which would correspond with the etched portion of an etched plate. Thereupon, the rubber can be deposited upon the parts of the plate not thus coated, thereby 40 creating the design to be impressed coated in relief on the base.

45 The accompanying drawings are illustrative of my invention, Figures 1, 2 and 3 representing vertical cross-sectional views and Figure 4 a sectional perspective view of a printing plate, briefed with suitable legends to indicate the nature of materials and the operations employed in carrying out my invention.

50 I contemplate the use of other materials than rubber for the coating, such as compounds and derivatives of rubber, resins, and other organic materials which are capable of electro-deposition and have the desired 55 characteristics of resilience or receptiveness to "water-color" inks, which materials are ordinarily of a colloidal nature. Where the term "rubber" is employed in the appended claims such materials are intended to be included.

60 I claim:

65 1. The method of producing printing plates having impression faces of rubber which consists in preparing a base having that portion of the surface thereof repre-

senting the design to be printed of electrical conducting material, and other portions of such surface of insulating material, and coating the first named portion with rubber by electro-deposition.

70 2. The method of producing printing plates having impression faces of rubber which consists in applying an insulating coating to one portion of an electrical conducting base so as to leave uncoated another portion representing the design to be printed, and forming on the uncoated portion of such base a layer of rubber by electro-deposition.

75 3. The method of producing printing plates having impression faces of rubber which consists in applying an insulating coating to the recessed portions of a metallic base carrying in relief the design to be printed, and subjecting said base to the action of an electro-deposition bath containing rubber or 80 the like, thereby to form a layer of rubber on the relief portions of said base.

85 In testimony whereof, I sign my name.
